UNITED STATES PATENT OFFICE.

ANDREW REESE, OF MASSILLON, OHIO.

DEVICE FOR DISPLAYING CARDS, ETC.

Application filed April 26, 1926. Serial No. 104,810.

This invention aims to provide a novel means for holding cards and the like, the construction of the article being such that its capacity may be increased by the addition 5 of one unit to another.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in perspective, a device constructed in accordance with the invention; and

Figure 2 is a side elevation.

The article forming the subject matter of this application preferably is made of wire, and includes side pieces 1 which are disposed in parallel relation throughout the major portion of their length, the side pieces being supplied at their upper ends with hooks 2 connected by a cross member 3 hav-

ing a suspension element 4, such as an up-standing loop. The card-holding means embodies any desired number of cross arms 5 connected to the side pieces 1 and supplied with upstanding fingers 6 at their ends, the fingers 6 being located about parallel to the side pieces 1.

In practical operation, the cards or other 40 objects which are to be held are thrust inwardly between the fingers 6 and the side pieces 1, and are supported by the cross arms 5. Any one article constructed as described above may be suspended by means of the 45 part 4. When it is desired to increase the capacity of the article, this is done by engaging the hooks 2 of one unit with the lowermost cross arm 5 of another unit, as shown in Figure 1, the article, thus, being continued 50 to any desired length, and the capacity being increased accordingly.

What is claimed is:—

An article of the class described, comprising side pieces and cross arms joining the 55 side pieces, the cross arms having angularly disposed fingers located about parallel with the side pieces but spaced therefrom, the fingers and the side pieces cooperating to hold an article.

In testimony that I claim the foregoing as my own, I have hereto affixed my signature.

ANDREW REESE.
